UNITED STATES PATENT OFFICE

STEPHEN H. COOGAN, OF ELSINORE, CALIFORNIA, ASSIGNOR TO COOGAN CONCRETE MACHINERY COMPANY LTD., OF ELSINORE, CALIFORNIA

MACHINE FOR MAKING CONCRETE PIPES

Application filed May 8, 1928. Serial No. 276,072.

This invention relates to machines for making concrete pipes, and has more particular reference to an improved machine of this kind in which power-operated means is provided for driving, and for raising a packer head relative to the mold in which the pipe is formed.

The primary object of the present invention is to provide improved manually-controlled power-operated means for slowly raising the packer head.

Another object is to provide efficient means whereby the concrete feed box is lifted from the mold as the packer approaches its upward limit of movement.

Still another object is to provide a machine of the above kind which embodies packer raising and driving means and feed box lifting means which are simple in character and efficient in operation.

The invention consists in the novel form, combination and arrangement of parts hereinafter more fully described, shown in the accompanying drawings and claimed.

In the drawings:

Figure 1 is a front elevational view of a machine, for making concrete pipes, embodying the present invention.

Figure 2 is a side elevational view thereof.

Figure 3 is a top plan view of the same; and

Figure 4 is an enlarged fragmentary horizontal section on line 4—4 of Figure 1.

Referring more in detail to the drawings, 5 indicates a suitable supporting frame having a top cross bar 6 at the front thereof to which are attached the upper ends of a pair of vertical rods 7. Carried by and arranged between the lower ends of the rods 7 is a gear casing 8 in which is journaled a horizontal worm gear 9, and which is also supported by a pair of spaced horizontal frame members 10 at a point well above the bottom of the frame. The gear casing 8 is thus effectively supported and held against turning, and journaled as at 11 on the front of the frame is a transverse horizontal drive shaft 12 whose inner end projects into the gear casing 8 and carries a worm 13 meshing with the worm gear 9. Extending through and

having a sliding key connection with the worm gear 9 is a vertical shaft 14 which is journaled in the casing 8 and has a packer head 15 on its lower end. Slidable on the rods 7 above the casing 8 is a horizontal bar 16 in which the upper end of the packer shaft 14 is journaled and from which said shaft is suspended as at 17.

Fixed to and depending from the ends of the bar 16 are a pair of rods 18 to which are connected, as at 19, the lower ends of a pair of hoisting cables 20 whose upper ends are attached to the respective ones of a pair of winding drums 21 secured on a transverse horizontal shaft 22 journaled on the top frame bar 6. Fixed on the ends of the shaft 22 are relatively large spur gears 23 which mesh with smaller gears 24 secured on the ends of a further transverse horizontal shaft 25 journaled on top of the frame 5 directly behind the shaft 22. Carried by the shaft 25 are a pair of spaced friction clutches 26 and 27, and the clutch 26 has a casing carrying a sprocket wheel 28, while the casing of the clutch 27 is suitably fixed to the frame 5 against turning. The casing of the clutch 26 and the sprocket wheel 28 are free to turn relative to the shaft 25 when the said clutch is disengaged, while rotation of the sprocket wheel 28 is transmitted to the shaft 25 when the said clutch is engaged. On the other hand, when the clutch 27 is disengaged the shaft 25 is free to turn, while engagement of said clutch 27 causes the latter to act as a brake to restrain the shaft 25 against turning. A double-ended actuator 29 for the clutches 26 and 27 is slidably carried by the shaft 25 between said clutches for selective independent engagement of the latter, whereby the shaft may be driven or held from rotation, at will. A shifting lever 30 is pivoted to the frame at its upper end and operatively connected intermediate its ends with the actuator 29, the lower end of the lever 30 being connected to the upper end of a hand operating lever 31 by means of a link 32, and the lever 31 being pivoted to one side of the frame 5 as at 33.

Journalized on top of the frame 5 to the rear of the shaft 25 is a still further horizontal

shaft 34 on which is fastened a small sprocket wheel 35 operatively connected to the larger sprocket wheel 28 by means of an endless sprocket chain 36. A further sprocket reduction gearing connects the shaft 34 with a shaft 37 mounted therebelow, as generally indicated at 38, and this shaft 37 is journaled behind the drive shaft 12 and operatively connected to the latter by yet another sprocket reduction gearing 39. In this way, a constant driving connection is provided between the drive shaft 12 and the sprocket wheel 28, embodying a series of reduction gears which cooperate to cause extremely slow vertical movement of the packer when the shaft 12 is driven and the sprocket wheel 28 is clutched to shaft 25 for causing the cables 20 to be wound on the drums 21. A pulley 40, or the like, may be provided on the outer end of the shaft 12 for connection with a suitable source of power, while a further pulley 41 may be carried by said shaft 12 to permit driving of a concrete mixer therefrom.

From the above description it will be understood that a mold 42 will be supported in position to have the pipe formed therein, the packer being slowly raised in the mold as the formation of the pipe proceeds, and the concrete being suitably dumped into a box 43 for being fed into the mold as the packer operates.

As shown, the feed box 43 rests on top of the mold and has lateral arms provided with guide sleeves 44 through which the rods 18 slidably extend. Stop members 45 are provided on the lower ends of the rods 18 and are adapted to engage the sleeves 44 as the packer 15 emerges from the upper end of the mold at completion of the pipe forming operation, whereby, upon continued upward movement of the rods 18 for a further short distance, the feed box 43 will be lifted off of the mold to permit its ready removal and substitution of an empty mold therefor. As soon as the feed box is lifted off of the mold, the clutch 26 is disengaged and the brake clutch 27 is engaged, thereby holding the feed box raised until the empty mold has been put in place. The brake clutch 27 is then partially released to allow the shaft 22 and drums 21 to turn and to permit the cables 20 to unwind at a proper speed for lowering the feed box onto the new mold and for also lowering the packer into said mold.

The frame 5 preferably has suitable guides 46 for the rods 18 below the gear casing 8 and just high enough to permit the feed box to be lifted entirely clear of the mold.

Minor changes may be made without departing from the spirit and scope of the invention as claimed.

What I claim is:

1. A machine for making concrete pipes comprising a vertically movable frame, a vertically disposed packer carrying shaft swivel-

ly connected at its upper end to said movable frame and supported thereby for vertical movement with said frame, a gear splined on said packer shaft, means for holding said gear in a fixed given horizontal plane, a worm gear meshing with said gear, a horizontally disposed power shaft for driving said worm gear, power means for driving said power shaft and for operating said packer shaft vertically, and hand operable means for actuating said power means, said hand operable means adapted when moved in one direction to actuate the packer shaft upwardly and adapted when moved in the other direction to brake the gravity descent of the packer shaft and all parts movable therewith.

2. A machine for making concrete pipe comprising a vertically movable frame, a vertically disposed packer carrying shaft having its upper end rotatably connected to and supported by said movable frame, a gear slidably splined on said packer shaft, means for holding said gear in a fixed given horizontal plane, a worm gear meshing with said gear, a power shaft supporting said worm gear, oppositely disposed stops carried by the vertically movable frame and adapted to engage the opposite sides of the mould hopper and a lift the latter at a predetermined time in an upward movement of said frame, power means for driving said power shaft and for operating said packer shaft vertically, and hand operable means adapted when moved in one direction to actuate the packer shaft upwardly and adapted when moved in the opposite direction to brake the gravity descent of the packer shaft and its correlated parts.

In testimony whereof I affix my signature.
STEPHEN H. COOGAN.
